US0D1090415S

(12) **United States Design Patent** (10) **Patent No.:** **US D1,090,415 S**
(45) **Date of Patent:** **** Aug. 26, 2025**

(54) **GLASS SOLAR PANEL**

(71) Applicant: **Clearvue Technologies Ltd**, West Perth (AU)

(72) Inventors: **Victor Rosenberg**, Yokine (AU); **Steven Coonen**, Grass Valley, CA (US)

(73) Assignee: **Clearvue Technologies Ltd**, West Perth (AU)

(**) Term: **15 Years**

(21) Appl. No.: **29/910,308**

(22) Filed: **Aug. 17, 2023**

(57) **CLAIM**

The ornamental design for a glass solar panel, as shown and described.

DESCRIPTION

FIG. 1 is a front view of a glass solar panel according to the claimed design;

FIG. 2 is a perspective view thereof;

FIG. 3 is a front view of another embodiment of a glass solar panel according to the claimed design;

FIG. 4 is a perspective view thereof;

FIG. 5 is a front view of another embodiment of a glass solar panel according to the claimed design;

FIG. 6 is a perspective view thereof;

FIG. 7 is a front view of another embodiment of a glass solar panel according to the claimed design;

FIG. 8 is a perspective view thereof;

FIG. 9 is a front view of another embodiment of a glass solar panel according to the claimed design;

FIG. 10 is a perspective view thereof;

FIG. 11 is a front view of another embodiment of a glass solar panel according to the claimed design;

FIG. 12 is a perspective view thereof;

FIG. 13 is a front view of another embodiment of a glass solar panel according to the claimed design;

FIG. 14 is a perspective view thereof;

FIG. 15 is a front view of another embodiment of a glass solar panel according to the claimed design; and,

(Continued)

FIG. 16 is a perspective view thereof.
